EXTENSION DEVICE

Sven O. Myrberg and George U. Meyer, Providence, R. I., assignors to Providence Stock Company, a corporation of Rhode Island

Application October 19, 1931, Serial No. 569,556

21 Claims. (Cl. 24—71)

Our present invention relates to the jewelry art, and has particular reference to extension devices for bracelets and watch straps.

Extension devices have heretofore provided a simple and effective method for temporarily lengthening a bracelet or a watch strap to permit movement over the wrist of the wearer. It has heretofore been proposed to also utilize an adjustment that will permit lengthening or shortening of the bracelet or wrist watch strap to more closely fit the wrist of the wearer when the extension device is in closed position, and such adjustments have been made either in the bracelet or watch strap or in the extension device itself.

Our present invention produces the desired length adjustment by utilizing a link that serves to connect the end of the bracelet or wrist watch strap to the extension device, the link being locked in desired set position by the closing of the extension device. This construction simplifies the adjusting operation, reduces the cost of manufacture by utilizing parts that may be formed by stamping, and enhances the appearance of the bracelet or wrist watch strap by permitting simulation of the bracelet or strap links by the adjusting link, with resultant concealment of any adjustment.

Moreover, we have found it feasible with the usual construction, to use the inherent resilience of the extension members as an adjustment lock, and to simplify and render more secure the releasable locking engagement of the parts of the extension device.

With these and other objects and advantageous features in view, our invention consists of a novel arrangement of parts more fully disclosed in the detailed description following, in conjunction with the accompanying drawing, and more particularly defined in the appended claims.

In the drawing,

Fig. 1 is a top plan view showing the extension device in closed position, and adjusted for length;

Fig. 2 is a bottom plan view similar to Fig. 1, with the extension device in extended position;

Fig. 3 is an enlarged central longitudinal section through the extension device shown in Fig. 1;

Fig. 4 is a perspective view of the extension device in open position;

Fig. 5 is a perspective view showing a modified form of link construction;

Fig. 6 is a perspective view showing a further modified form of link construction, preferably struck from sheet stock; and

Fig. 7 is a fragmentary view showing a modified projection.

Referring to the drawing, the extension device has a top plate 10 which is hingedly connected to one end of a bracelet or watch strap 11 by means of folding members, and is hingedly connected to the other end of the bracelet or watch strap through an intermediate adjusting link 13 which is slidably mounted in the top plate 10. The adjusting link 13 is preferably made in two parts 10 comprising a U-shaped part 14 which is preferably made of wire, and which has recesses 15 at the ends of the sides of the U adapted to receive the trunnion-like pins 16 of an adjustment plate 17; the sides of the U slide in channels 18 formed in the top plate 10 of the extension device and the adjusting link as a whole is slidably locked to the top plate by the bent over lip or edge 19 of the top plate.

An intermediate plate 20 is hinged to the other end of the top plate and a bottom plate 21 is hingedly connected to the intermediate plate. The intermediate plate, as shown in Figs. 2 and 4, has a projection 22 which is positioned on the upper face centrally between the side edges of the plate and intermediate the ends thereof, this projection being preferably struck up or forced up from the plate material, which projection is selectively engageable with any one of a series of slots 23 which are positioned between the side edges 26a of the adjustment plate and which extend in a successive series along the length of the adjustment plate. The bottom plate 21 has spaced catch projections 24 preferably positioned at both ends thereof, for releasably engaging the edges of the channels 18 to detachably lock the lower plate to the top plate with the intermediate link nested therebetween. A finger tab 25 is positioned at one end of the upper plate, as shown in Fig. 1, to permit manual disengagement of the top and bottom plates for extending the extension device.

The operation of the improved construction is as follows: With the extension device in open position, the adjusting link 13 may be slidably moved with respect to the top plate 10, to obtain a desired length for the bracelet or watch strap; the extension device now being closed, the projection 22 will selectively engage one of the slots 23 of the adjustment plate and will be pressed in place due to the inherent resilience of the intermediate plate; the closing of the lower plate over the intermediate plate and the locking of the extension device in closed position by engagement of the catches 24 with the sides of the

channels 18 then positively secures the parts against relative opening movement.

Instead of using an adjustment plate 17 formed as shown in Fig. 2, it may be desirable in certain 5 constructions of bracelets and watch straps, particularly those of relatively great width, to form the adjustment plate as indicated at 26 in Fig. 5, the forward end having laterally extended sides 27 which snugly engage the sides of the channels 10 18 for preventing tilting movement of the adjustment plate and obtaining a firmer bearing.

The above described construction of adjusting link permits manufacture of the U shaped part 14 from wire or the like, thus reducing the cost 15 and at the same time permitting simulation of the bracelet links when used with link bracelets, however, the adjusting link and adjustment plate may, if desired, be made integral, as from sheet stock or the like as shown at 28 in Fig. 6, the 20 blank being cut so as to provide laterally extended sides which may be rolled to form the sides 29 of the U shaped portion.

Instead of using a relatively square projection, as shown in Fig. 4, a saw tooth projection 25 30 may be used instead, formed as shown in Fig. 7. The projection is slanted so as to permit adjusting inward movement of the adjusting link when the extension device is in closed position, but to lock against outward movement.

30 Our novel construction, therefore, utilizes an adjusting link which cooperates with an extension device to provide a length adjustment for the bracelet or watch strap. The U shaped member when used with bracelets or watch straps of link construction simulates the link formation, as shown in Fig. 1, and thus adds to the attractiveness and neat appearance of the device. The novel adjustment for length thus includes a 35 slideable part which is slidably mounted in the extension device and is positively locked in adjusted position upon closure of the extension device parts.

Having thus described specific embodiments of our invention, it is obvious that changes in the 45 arrangement, and in the relative proportion and size of the parts, may be made to suit the requirements of particular types of bracelets and watch straps, without departing from the spirit and the scope of the invention as embodied in the 50 appended claims.

We claim:—

1. In an extension device, an upper plate, a lower plate, an intermediate plate hingedly connecting the upper and the lower plates, an adjustment link slidably mounted in said upper plate, and cooperating means in said intermediate plate and said adjustment link comprising a series of spaced detents on the adjustment link and a projection on the intermediate plate selectively engageable with said detents for selectively setting said link in desired longitudinal relation to said upper plate, said means being inoperative when the plates are in extended position but operative when the plates are in closed position to prevent lengthwise movement of the adjustment link in the upper plate in a direction to extend the same but to permit lengthwise movement of the adjustment link in the upper plate in a direction to contract the same while the plates are in closed position.

2. In an extension device for a bracelet, two sliding members connected to slide endwise one upon the other, means constituting a connecting link between the sliding members and one end

of the bracelet, said means including an intermediate member hinged to one of the sliding members, and cooperating means on the intermediate member and the other sliding member comprising ratchet means on the other sliding member and a pawl on the intermediate member and inoperative when the intermediate member is in open position but operative when the intermediate member is folded over in closed position upon the sliding members to prevent lengthwise adjustment of the two sliding members in a direction to extend the same but to permit lengthwise adjustment of the two sliding members in a direction to contract the same while the folding member is in closed position.

3. In an extension device for a bracelet, two sliding links connected to slide lengthwise one upon the other and to project one beyond the other when in extended position, means constituting a connecting link between the sliding links 20 and one end of the bracelet, said means including an intermediate link hinged to one of the sliding links, said intermediate link and the other sliding link respectively having cooperating pawl and ratchet means in operative engagement only 25 when the intermediate link is in closed position with relation to the sliding links, said pawl and ratchet means being so formed that when in operative engagement they will hold the sliding links releasably in any one of several positions 30 of lengthwise adjustment between the sliding links and permit a lengthwise adjustment between the sliding links for a relatively small adjustment of the extension device.

4. In an extension device, an upper plate having side flanges, said side flanges being turned inwardly to form spaced aligned edges, a lower plate having lateral extensions, an intermediate member hingedly connecting the upper and lower plates and adapted to be received between 40 said lateral extensions, said lower plate and said intermediate member being folded between said spaced edges when said extension device is in closed position, one of said plates having longitudinally spaced catch elements releasably 45 engageable with the edges of the other plate to hold the lower plate and intermediate member in folded relation.

5. In an extension device, an upper plate having side flanges, said side flanges being turned 50 inwardly to form spaced aligned edges, a lower plate having lateral extensions, an intermediate member hingedly connecting the upper and lower plates and adapted to be received between said lateral extensions, said lower plate and said intermediate member being folded between said spaced edges when said extension device is in closed position, said lower plate having lateral longitudinally spaced catch elements for releasably 55 engaging the spaced edges of the upper plate.

6. In an extension device, an upper plate having side flanges, said side flanges being turned inwardly to form spaced aligned edges, a lower plate having lateral extensions, an intermediate member hingedly connecting the upper and lower plates and adapted to be received between said lateral extensions, said lower plate and said intermediate member being folded between said spaced edges when said extension device is in closed position, said lower plate having catch elements at each end thereof for releasably engaging the spaced edges of the upper plate.

7. In a foldable bracelet buckle a plurality of 75

sections hinged together to fold one on the other in overlying relationship, a member slidably mounted in one section, interengaging means on said member and another section comprising a series of abutments on said member and a tongue of extended length integral with said other section, and extending over, the stock of said member.

8. In an extension device, an upper plate, a lower plate, an intermediate plate hingedly connecting the upper and the lower plates, an adjustment link slidably connected to said upper plate, and cooperating means in said intermediate plate and said adjustment link comprising a series of spaced detents on the adjustment link and a projection on the intermediate plate selectively engageable with said detents for selectively setting said link in desired longitudinal relation to said upper plate, said means being inoperative when the plates are in extended position but operative when the plates are in closed position to prevent lengthwise movement of the adjustment link with respect to the upper plate in a direction to extend the same but to permit lengthwise movement of the adjustment link with respect to the upper plate in a direction to contract the same while the plates are in closed position.

9. In an extension device, an upper plate, a lower plate, an intermediate plate hingedly connecting the upper and the lower plates, an adjustment link slidably connected to said upper plate, and cooperating means in said intermediate plate and said adjustment link comprising a series of spaced detents on the adjustment link and a projection on the intermediate plate selectively engageable with said detents for selectively setting said link in desired longitudinal relation to said upper plate.

10. In an extension device, an upper plate, a lower plate, an intermediate plate hingedly connecting the upper and the lower plates, an adjustment link slidably mounted in said upper plate, and cooperating means in said intermediate plate and said adjustment link comprising a series of spaced detents on the adjustment link and a projection on the intermediate plate selectively engageable with said detents for selectively setting said link in desired longitudinal relation to said upper plate.

11. In a bracelet structure, extensible means for connecting the ends of a pair of bracelet sections comprising a supporting member provided with inturned lateral edges forming guideways, an extension member provided with longitudinally extending spaced lateral portions slidably mounted within the guideways of said supporting member and having a portion located intermediate of and connecting said lateral portions, a foldable member pivotally connected to said supporting member and movable into folded relation therewith, and means carried by said foldable member and the intermediate portion of said extension member engageable when the foldable member is in its folded position relative to said supporting member to lock said extension member against lengthwise sliding movement in either direction relative to said supporting member.

12. In a bracelet structure, extensible means for connecting the ends of a pair of bracelet sections comprising a supporting member provided with inturned lateral edges forming guideways, an extension member provided with longitudinally extending spaced lateral portions slidably mounted within the guideways of said supporting

member, means carried by said spaced lateral portions and located intermediate thereof for engagement with cooperating means carried by a foldable member, a foldable member pivotally connected to said supporting member and movable into folded relation therewith, and means carried by said foldable member engageable with the means carried by the spaced lateral portions of said extension member when the foldable member is in its folded position relative to said supporting member to lock said extension member against lengthwise sliding movement in either direction relative to said supporting member.

13. In an extension device, an upper plate, a lower plate, an intermediate plate hingedly connecting the upper and lower plates, an adjustment link slidably mounted in said upper plate, and cooperating lock means on said intermediate plate and said adjustment link comprising a series of detents and a projection selectively engageable with said detents for selectively locking said link in desired longitudinal relation to said upper plate, said means being inoperative when the plates are in extended position but operative when the plates are in closed position to prevent lengthwise movement of the adjustment link in the upper plate.

14. In an extension device, an upper plate, a lower plate, an intermediate plate hingedly connecting said upper and lower plates, and an adjustment link slidably connected to said upper plate, said link and said intermediate plate having cooperating means for selectively setting and locking said link in desired longitudinal relation to said upper plate.

15. In an extension device, an upper plate, a lower plate, an intermediate plate hingedly connecting said upper and lower plates, and an adjustment link slidably mounted in said upper plate, said link and said intermediate plate having cooperating means for selectively setting and locking said link in desired longitudinal relation to said upper plate.

16. In an extension device, an upper plate, a lower plate, an intermediate plate hingedly connecting the upper and the lower plates, an adjustment link slidably connected to said upper plate, and cooperating means in said intermediate plate and said adjustment link for selectively setting said link in desired longitudinal relation to said upper plate, said means being inoperative when the plates are in extended position but operative when the plates are in closed position to prevent lengthwise movement of the adjustment link with respect to the upper plate in a direction to extend the same but to permit lengthwise movement of the adjustment link with respect to the upper plate in a direction to contract the same while the plates are in closed position.

17. In an extension device, an upper plate, a lower plate, an intermediate plate hingedly connecting the upper and the lower plates, an adjustment link slidably connected to said upper plate, and cooperating means on said intermediate plate and said adjustment link comprising a series of detents and a projection selectively engageable with said detents for selectively setting said link in desired longitudinal relation to said upper plate, said means being inoperative when the plates are in extended position but operative when the plates are in closed position to prevent lengthwise movement of the adjustment link in the upper plate in a direction to extend the same but to permit lengthwise movement of the adjustment link in the upper plate in a di-

rection to contract the same while the plates are in closed position.

18. In an extension device, an upper plate, a lower plate, an intermediate plate hingedly connected to the upper and the lower plates, an adjustment link slidably connected to said upper plate and adjustable cooperating means in said intermediate plate and said adjustment link positioned intermediate the side edges thereof for selectively setting said link in desired longitudinal relation to said upper plate, said means being inoperative when the plates are in extended position but operative when the plates are in closed position to prevent lengthwise movement of the adjustment link with respect to the upper plate in a direction to extend the same but to permit lengthwise movement of the adjustment link with respect to the upper plate in a direction to contract the same while the plates are in closed position.

19. In an extension device, an upper plate, a lower plate, an intermediate plate hingedly connecting the upper and the lower plates, an adjustment link slidably connected to said upper plate, and adjustable cooperating means in said intermediate plate and said adjustment link positioned intermediate the side edges thereof for

selectively setting said link in desired longitudinal relation to said upper plate.

20. In an extension device, an upper plate, a lower plate, an intermediate plate hingedly connecting the upper and the lower plates, an adjustment link slidably mounted in said upper plate, and adjustable cooperating means in said intermediate plate and said adjustment link positioned intermediate the side edges thereof for selectively setting said link in desired longitudinal relation to said upper plate.

21. In an extension device, an upper plate having side flanges extending downwardly therefrom and turned inwardly to form spaced aligned edges, a lower plate having side flanges, an intermediate member hingedly connecting the upper and lower plates and adapted to be received between said lower plate side flanges, said lower plate and said intermediate member being folded between said upper plate spaced edges when the extension device is in closed position, said lower plate side flanges having catch elements for releasably engaging the spaced edges of the upper plate.
